UNITED STATES PATENT OFFICE.

DELBERT WARD, OF LITTLE ROCK, ARKANSAS, ASSIGNOR OF FORTY PER CENT TO
JOHN H. WALLACE, OF LITTLE ROCK, ARKANSAS.

ATTACHMENT FOR PLAYER PIANOS.

Application filed September 1, 1921. Serial No. 497,606.

To all whom it may concern:

Be it known that I, DELBERT WARD, a citizen of the United States, residing at Little Rock, in the county of Pulaski and State of 5 Arkansas, have invented certain new and useful Improvements in Attachments for Player Pianos; and I do declare the following to be a full, clear, and exact description of the invention, such as will enable others 10 skilled in the art to which it appertains to make and use the same.

This invention relates to an attachment for a player piano and one object of the invention is to provide a device which can 15 be installed in connection with a player piano of a conventional construction and which when in place will be operatively connected with the bellows usually operated by the foot pedals and serve to move these 20 bellows. It will thus be seen that with this attachment, the usual foot pedals can be dispensed with and the player piano operated by simply pressing a button to close the 25 circuit of an electric motor.

Another object of the invention is to provide a device which can be operatively connected with the usual drive shaft of the 30 bellows.

Another object of the invention is to so 35 construct this attachment that it may be mounted in the lower portion of the piano where it will be out of the way and out of view.

This invention is illustrated in the accompanying drawings, wherein:

Figure 1 is a vertical sectional view 40 through the lower portion of a player piano having the improved device installed therein.

Figure 2 is a transverse sectional view taken along the line 2—2 of Fig. 1.

Figure 3 is a vertical sectional view taken along the line 3—3 of Fig. 1.

The player piano indicated in general by 45 the numeral 1 is of a conventional construction and is provided with the usual player mechanism including bellows 2. This player mechanism is not shown completely or described in detail since it is only intended to 50 indicate any desired conventional type of player mechanism which includes the bellows 2 ordinarily operated by means of foot pedals which will be removed when it is desired to install this motor driven mechanism 55 in place of the usual foot pedals and means

connecting the foot pedals with the bellows.

The motor 3 is to be mounted in the lower portion of the piano casing and supplied with current by suitable conductor wires and also connected with a suitable switch 60 conveniently located upon the keyboard or adjacent the keyboard so that by pressing the button of the switch, the current may be turned on and the motor started. This motor rotates a shaft 4 which is journalled 65 in bearings 5 and carries a worm 6 for meshing with the teeth of a large gear disk 7. This gear disk 7 is rotatably mounted in a horizontal position by means of a bearing 8 and is provided with upwardly extending 70 pin teeth 9 for engaging the teeth of a pinion or gear 10 upon a shaft 11 and transmitting rotary movement to this shaft 11 when the motor is in operation. This shaft 11 is journalled in bearings 12 and is provided at its 75 ends with crank extensions 13 with which are connected links 14. These links 14 are connected with the bellows 2 and it will be readily seen that when the shaft 11 is rotating, the links 14 will be reciprocated and thus the proper movement given to the bellows.

When installing this device, it is simply necessary to remove the usual foot pedals and the connections between the pedals and the bellows and then put the motor in place with its shaft 4 journalled in the bearing 5 which will be secured to the baseboard of the casing. The gear disk 7 will be put in place with its teeth meshing with the worm 80 6 and the shaft 11 will then be put in place with its gear 10 engaged by the teeth 9 of the gear 7 and the links 14 will be connected with the bellows. The necessary switch which may be of any suitable type will be 85 put in place and with the necessary wiring installed, it is only necessary to close the switch thus starting the motor. After the piece has been played the rewinding lever 90 of the usual mechanism can be moved to rewind the ribbon and the switch then opened to shut off the motor. It will thus be seen that this device is so constructed that it can be installed in connection with a player piano having a conventional construction 105 and therefore can be sold either as a part of a piano when first manufactured or can be sold as an attachment and put in place in connection with a piano already in use.

In order to prevent damage by excessive 110

air pressure when playing a piece of music, portions of which are fast and portions of which are slow and in order to prevent damage in cast the strip of record should hang, 5 there has been provided an escape valve 15 for each of the bellows. These valves have the usual safety valve constructions so that they will normally remain closed but may be forced opened when the air pressure in- 10 creases beyond a desired amount. It will thus be seen that with this escape valve in place, the motor can run at the same speed at all times and the air pressure will be prevented from reaching such a point that 15 damage would be done to the player mechanism of the piano.

I claim:

1. In combination with a piano including a casing and player mechanism in the casing 20 having operating bellows positioned above the bottom of the casing and in spaced relation to each other, a flat gear disk rotatably connected with the bottom of the casing between the bellows and positioned in a horizontal plane and having worm teeth about its periphery and having pin teeth extending from its upper face adjacent its periphery, a drive shaft rotatably mounted in bearings secured to the bottom of the casing, a 25 worm carried by the drive shaft and meshing with the worm teeth of said gear disk for imparting rotary movement to the gear disk, a crank shaft rotatably mounted in bearings carried by the bottom of the casing and extending over said gear disk, a pinion carried by said crank shaft and positioned for engagement by the pin teeth of the gear disk, and links connecting the crank portions of the crank shaft with said bellows 30 for imparting operative movement to the bellows when the crank shaft is rotating.

2. In combination with a piano including a casing and player mechanism in the casing having operating bellows positioned above

the bottom of the casing and in spaced relation to each other, of bellows operating means comprising a drive shaft rotatably mounted in said casing adjacent the bottom and to the rear of said bellows, a crank shaft rotatably mounted in the casing in the forward portion thereof and adjacent the bottom of the casing, links connecting the crank shaft with the bellows for imparting movement to the bellows when the crank shaft is rotating, a gear disk rotatably connected 55 with the bottom of the casing and extending horizontally therein with one portion extending beneath said crank shaft, a pinion carried by said crank shaft above said gear disk, teeth extending upwardly from said gear disk, and engaging said pinion for imparting rotary movement to the crank shaft when the gear is rotating, and means for transmitting rotary movement from said drive shaft to said gear disk. 65

3. In combination with a piano of the upright type including a casing and player mechanism in the casing including bellows positioned in the lower portion of the casing with the bellows positioned in spaced relation to each other and above the bottom of the casing, of bellows operating means comprising a bearing secured to the bottom of the casing between the bellows, a gear disk rotatably mounted in said bearing, a crank shaft rotatably mounted in the casing and extending between the bellows and beneath the plane of the lower ends of the bellows, links connecting the crank shaft with the bellows for imparting movement to the bellows when the crank shaft is rotating, means in the lower portion of the casing for imparting rotary movement to said gear disk, and means for transmitting rotary movement from the gear disk to the crank shaft. 75 80 85

In testimony whereof I have hereunto set my hand.

DELBERT WARD.
